CLAIM

We claim the ornamental design for a tire for a model vehicle, as shown and described.

DESCRIPTION

FIG. 1 is an upper, left, rear perspective view of a tire for a model vehicle;

FIG. 2 is front plan view thereof;

FIG. 3 is a left side elevation view thereof;

FIG. 4 is a right side elevation view thereof;

FIG. 5 is a top plan view thereof; and,

FIG. 6 is an upper, left rear perspective environmental use view.

In the drawings, the broken line showing of features of the tire for a model vehicle illustrate portions of the tire for a model vehicle that form no part of the claimed design; whereas, the broken line showing of the environmental use view depicts environmental subject matter and is provided for the purposes of illustrating environmental use structure and context.

In the drawings, only the front plan view and top plan view are shown. The corresponding rear plan view and bottom plan view are mirror images of the front plan view and top plan view and are included in the scope of the claim.
